UNITED STATES PATENT OFFICE.

WESTON F. WILLIAMS, OF FALLS CHURCH, VIRGINIA.

BOILER.

1,383,179.

Specification of Letters Patent. Patented June 28, 1921.

Application filed July 17, 1919. Serial No. 311,642.

To all whom it may concern:

Be it known that I, WESTON F. WILLIAMS, a citizen of the United States, residing at Falls Church, in the county of Fairfax and 5 State of Virginia, have invented certain new and useful Improvements in Boilers; and I do hereby declare the following to be a full, clear, and exact description of the invention, such as will enable others skilled in the art 10 to which it appertains to make and use the same.

This invention relates to improvements in steam generators and particularly to the so-called sectional or unit type of boiler.

15 It is one of the objects of the present invention to improve the construction of unit or sectional type boilers to increase the heating capacity of the same by providing a maximum traverse for the heated gases in 20 their escape from the boiler and at the same time to provide for the highest abstraction of heat from the gases consistent with a proper draft through the boiler. A further object of the present invention is to provide 25 for the safety of the boiler and for a reliable action of the circulation by the equalization of the water level in the various units and a proper distribution of the steam generated in the several units to secure 30 an efficient flow of the water as it is being heated and to facilitate the collection of the steam in the steam head or drum and it is another object of the invention to provide 35 improved facilities for cleaning the flues forming the channels or passageways through which the gases pass.

With these and other objects in view, the invention consists in the construction, the combination, and in details and arrangements 40 of the parts as more particularly disclosed hereinafter relative to the embodiment of the invention illustrated in the accompanying drawings, in which:

Figure 1 is a perspective view of the scattered boiler units but shown in position to 45 indicate clearly the path of travel of the gases.

Fig. 2 is a perspective view of the assembled boiler.

50 Fig. 3 is a perspective view of the back unit section of the boiler.

Fig. 4 is a front end elevation of the inside face of the rear end of the boiler partly broken away to indicate the hollow walls.

55 Fig. 5 is a face view of the inside face of

the front unit of the boiler partly broken away.

Fig. 6 is a side elevation of an intermediate unit partly broken away.

Fig. 7 is a longitudinal section of the 60 boiler on line 7—7 of Fig. 4.

Fig. 8 is a longitudinal section of the boiler on line 8—8 of Fig. 4.

The present boiler as illustrated comprises a front and feeding head or unit section 2 shown as a generally rectangular form in elevation and provided with ash removal doors 3 and upper firing doors 4 and above these with a series of flue closures generally indicated at 5, these being designed to 70 cover the cleanout holes 6 extending through the front unit, the inside face of which is clearly shown at the right of Fig. 1 and also in Fig. 5. This front unit section has its wall structure preferably tubular or hollow as is indicated at 7 in Fig. 5, so that water may be readily circulated through the various passageways in the hollow walls to derive heat from the gases passing through the flues or passageways of the boiler, water 80 being admitted to the hollow walls by any suitable means as for instance comprising a header or headers, these preferably arranged one on each side of the boiler and indicated at 8 to which headers water is 85 supplied through respective water to feed pipes 9, Fig. 2. Each header is connected to the several units to be described hereafter through nipples as at 10, Fig. 5, in which is clearly seen how the headers or 90 manifolds are connected to the front unit 2.

The rear unit 15 of the boiler is likewise constructed of hollow walls for a circulation of water as it is heated.

The intermediate units of the boiler are 95 relatively thinner than the front and rear units though not essentially so and are formed of solid walls but are hollow in form and as clearly shown at 20 in Figs. 1 and 6 are provided with numerous transverse apertures 21, that is apertures extending from side face to side face of each unit, these apertures obviously registering with one another in given planes when the units are assembled, and clamped between the front 100 and rear sections, suitable clamping means being indicated at 22, Fig. 2. The apertures or flue holes 21 in the intermediate units are so disposed and so shaped and are of such area as to enable the quite free travel of 110

heated gases as fire is made and maintained above the grate 25 which may be operable by suitable means as levers 26. The generated gases pass rearwardly from the firebox 5 beneath the crown or arch 21^a formed by the assembled intermediate units 20, and moving rearwardly pass up over a deflecting hollow wall 16 and into back ports 17 which are centrally divided by an upright portion 18 10 which causes the division of the gaseous product so that it is caused to return in the direction of the arrows *a*, Fig. 7, through the lowermost row of pockets or apertures 21 and issue into a pocket or chamber 19 in 15 the lower portion of the front unit 2 from which it passes through the next higher horizontal row of apertures 21 in the path indicated at *b* the front section having also a vertical partition 18 for controlling the 20 direction of travel to lead the gaseous products into adjacent openings 21. After traversing in the path indicated at *b* the rearwardly moving gases enter pairs of pockets 21^a on each side of the partition 18 of the 25 back unit and rising in this, pass forwardly in the path *c* through the next horizontal series of openings 21 and into a pair of upper chambers 19^a from whence they pass rearwardly again through the path *d* in the 30 uppermost row of pockets 21 from which they issue into transversely extending passageways 17^c which are also extended downwardly as at 17^d along the legs or outer portions of the back section 15, the vertical 35 component of these passageways uncovering a series of openings 21^b at the sides of the units 20 thence through the paths *e*, Fig. 8, toward the front section and into vertically extending chambers or pocket 27 which 40 change the gaseous travel, as indicated, to the lower outlets or passageways 21^e of the intermediate units from which they pass into a rearmost passageway 28 extending across the back of the back unit or section, the incoming gases converging as at *f* and rising 45 through the uptake 29 which may be provided with a clean out cover 30, thence the gases pass into an opening or chamber 31 in the top of the back section 15, see Fig. 1, 50 and pass thence in the path *g*, Fig. 8, through alined apertures 32, Fig. 6, in the intermediate units from which they enter a horizontally extending and uppermost pocket or chamber 33 in the front section 2, 55 across which they travel as plainly shown in Fig. 1 to enter alined apertures 34 through which they travel rearwardly an outlet or chimney connection 35. There may be mounted in this connection if desired any suitable draft controlling device as a damper 36 with its usual or suitable controlling 60 means 37.

From the above it will be seen that I have provided for an extremely extensive circuit in which the gases produced by combustion

are caused to travel and thereby enable the best absorption of the heat from the gases, first owing to the direct contact of the heat with the walls of the pockets in the intermediate sections which pockets are surrounded by a body of water and second, I utilize the heat in the front and rear sections, which latter are provided with hollow walls, having connecting chambers through which the water can freely circulate and steam readily rise.

In order to secure a sufficient and effectual balance of the pressure and circulation in the apparatus, the bottom manifolds or headers 8 are provided with stand pipes 8^a extending upwardly and having horizontal branches 8^b leading inwardly toward a center or steam head 40 from which any suitable number of outtake steam pipes 41 may be run. If desired, and preferably, 85 a suitable safety device, as a valve 42, may be provided on the steam head 40 and a water level gage 43 may be introduced into one or any of the stand pipes 8^a to indicate water level in the boiler. From this it will be seen 90 that water can freely circulate from the header or manifolds 8 by direct connection through each of the units of the boiler and can rise and fall in the stand pipes 8^a because of the effectual balance which I secure through the connection of the stand pipes and between the water manifolds 8 and the steam head 40.

The steam arising in each of the intermediate units 20, which I preferably form of such construction that they are relatively sealed as between each other, passes out of the steam outlets 20^a into nipples connecting them to the steam head 40 while steam generated in the intercommunicating passageways in the hollow walls in the rear and front units may collect in steam chambers 45 in each and thence passes into the steam head 40 as through a connecting nipple or nipples 46, Fig. 4.

What I claim is:

1. In a boiler of the unit section type, a front unit member, a back unit member and a series of intermediate sections having non-intercommunicating side wall faces arranged in abutting juxtaposition and provided in the outermost or lateral outermost edge faces and at the lower portion thereof with water inlet openings and having in the top faces a steam outlet, the said intermediate units being hollow and having series of horizontal rows of smoke passageways in which the gaseous products are caused to flow alternately in reverse directions in successively higher planes, the back unit having a pair of adjacent L-shaped pockets diverting the gas from the upper row of passageways in the intermediate units outwardly toward outer vertical rows of passageways, the gas flowing downwardly through the vertical legs

- of the L-shaped pockets in the rear unit and passing forwardly through certain of the passageways in the intermediate units into vertical lateral pockets in the front member 5 which divert the gases downward to co-ordinate return pockets in the intermediate units, the back member having a collecting flue with an upstanding centrally arranged branch, the intermediate sections having in 10 the upper portion alined series of passageways through one series of which the gas is directed from the centrally arranged branch and returned on the opposite side of the units, the front and rear unit members having 15 hollow partition walls forming independent pockets or chambers on opposite sides of a central vertical partition.
2. In a boiler of the unit section type, a front unit member and a back unit member, 20 and a series of intermediate sections having non-intercommunicating side wall faces arranged in abutting juxtaposition and provided with water inlet openings at the lower portion thereof and having a steam outlet 25 in the top faces, the said intermediate units being hollow and having series of horizontal rows of smoke passageways in which the gaseous products are caused to flow alternately in reverse directions in successively 30 higher planes, the intermediate sections having in the upper portion, alined series of passageways through one series of which the gas is directed on one side of the units and returned on the opposite side of the units, 35 the front and rear unit members having partition walls forming independent pockets or chambers on opposite sides of a central, vertical partition, the rear section having two of its pockets, one on each side of the 40 center wall, arranged to register with respective parts of the lowermost series of spaces in the intermediate sections so as to divert the travel of gases through the lowermost row of spaces, the front section having a pair of pockets on a common horizontal 45 plane, each pocket coördinate with a group of passageways on opposite sides of the vertical plane of the boiler so as to receive the gases from the lowermost row of openings in the intermediate units and divert it into 50 the next higher row of coördinate openings; the rear unit having a pair of adjacent chambers coördinate with respective groups of openings in the intermediate section to receive gas from a relatively horizontal row 55 of spaces and divert the same into the next higher row; the front unit having an upper pair of adjacent pockets coördinate to respective groups of rows of passageways in 60 the intermediate units to divert the gases into the uppermost of the coördinate rows; the back unit having a pair of adjacent L-shaped pockets to divert the gas from the upper row of passageways outwardly toward outer, vertical rows of passageways, 65 the gas flowing downwardly through the vertical legs of the L-shaped pockets in the rear unit and passing forwardly through the outer vertical row of openings into vertical, lateral pockets in the front member which 70 divert the gases downwardly to coöordinate return pockets in the intermediate units; the back member having a collecting flue with an upstanding, centrally arranged branch; and lateral passageways formed in the upper portion of the assembled units through 75 one series of which the gas is directed from the top of the branch and subsequently returned along the opposite side of the boiler to an outlet.

In testimony whereof I affix my signature.
WESTON F. WILLIAMS.
